CLAIM

The ornamental design for a two valve nozzle for a CO₂ snow cleaner.

DESCRIPTION

FIG. 1 is a front perspective view of a two valve nozzle for a CO₂ snow cleaner showing my new design;

FIG. 2 is a side elevation view thereof, the opposite side is a mirror image thereof;

FIG. 3 is a top plan view thereof;

FIG. 4 is a bottom plan view thereof;

FIG. 5 is an enlarged front end elevational view thereof; and,

FIG. 6 is an enlarged rear end elevational view thereof.
